ABSTRACT OF THE DISCLOSURE

One face of a transducer element is acoustically coupled to a matched termination having a characteristic impedance greater than that of the surrounding medium. The termination causes cancellation by phase interference of an acoustical wave generated by the transducer element and reflected back to the transducer element from the interface between the end of the termination and the surrounding medium.

**BACKGROUND AND SUMMARY OF THE
INVENTION**

This invention relates to ultrasonic transducers and, more specifically, to an improved termination for use therewith.

One face of a damped transducer element is typically terminated in a lossy backing material having a characteristic impedance that matches the characteristic impedance of the transducer element. The termination is made sufficiently long (about an inch or more) that an acoustical wave reflected from the interface between the end of the termination and the surrounding medium is attenuated enough to prevent it from having an appreciable effect upon the transducer element. This either prevents the reflected acoustical wave from being detected by the transducer element or makes it readily distinguishable from other acoustical waves detected by the transducer element.

It is the principal object of this invention to reduce both the length of the termination and the net effect upon the transducer element of the acoustical wave reflected back to the transducer element from the interface between the end of the termination and the surrounding medium. This object is accomplished according to the preferred embodiment of this invention by providing a drastically shortened termination (about fifty thousandths of an inch long) having a characteristic impedance very much greater than that of the surrounding medium. Notches are formed in the end of the termination so that one half of an acoustical wave transmitted from the transducer element to the interface between the end of the termination and the surrounding medium is reflected from the interface one more time than the other half and so that both halves are reflected back to the transducer element along paths of equal length in time. The effect upon the transducer element of one half of the reflected acoustical wave is therefore cancelled by that of the other half.

**DESCRIPTION OF THE PREFERRED
EMBODIMENT**

Referring now to the drawing, which is a perspective view of an ultrasonic transducer according to the preferred embodiment of this invention, there is shown a transducer element such as a piezoelectric crystal 10. Electrically conductive metal electrodes 12 and 14 are bonded to opposite and parallel faces of the piezoelectric crystal 10. A source 16 of electrical signal for energizing the piezoelectric crystal 10 is connected to the

2

electrodes 12 and 14. Upon being energized the piezoelectric crystal 10 generates one acoustical wave that propagates in the forward direction 18 and another acoustical wave that propagates in the reverse direction 20. A termination 22 made of a lossy material is bonded to the electrode 14 to attenuate the acoustical wave that propagates in the reverse direction 20. This termination 22 is only about fifty thousandths of an inch long. It may be described as an acoustic transmission line having a characteristic impedance Z_{01} that is matched to the characteristic impedance of the piezoelectric crystal 10 and that is very much greater than the characteristic impedance Z_{02} of the surrounding medium, for example, air.

The reflection coefficient Γ of the interface 24 between the end of the termination 22 and the surrounding medium is given by

$$P_2/P_1 = \Gamma = (Z_{02} - Z_{01})/(Z_{02} + Z_{01})$$

where P_1 is the magnitude of the acoustic wave generated by the piezoelectric crystal 10 and incident upon the interface 24 (hereinafter referred to as the incident acoustical wave), and P_2 is the magnitude of the acoustic wave reflected from the interface 24 back to the piezoelectric crystal 10. The magnitude P_3 of the acoustic wave transmitted through the interface 24 and into the surrounding medium is given by

$$P_3 = (1 + \Gamma)P_1$$

Since Z_{01} is very much larger than Z_{02} , Γ is approximately equal to minus one. This indicates that there is one hundred and eighty degrees phase shift and almost one hundred percent reflection of each portion of the incident acoustic wave each time it is reflected from the interface 24. The incident acoustic wave may therefore be cancelled by phase interference if one half of the incident acoustic wave is reflected from the interface 24 one more time than the other half and if both halves are reflected back to the piezoelectric crystal 10 along paths of equal length in time.

Accordingly, the termination 22 is provided with flat end portions A and notched end portions B that are alternately arranged so that the flat end portions A are collectively positioned directly opposite half of the piezoelectric crystal 10 and so that the notched end portions B are also collectively positioned directly opposite half of the piezoelectric crystal. The flat end portions A all lie in a reference plane 26 that is parallel to the faces of the piezoelectric crystal 10 and that normally intersects the sides of the termination 22. One half of the incident acoustic wave is therefore reflected once with a minimum reduction in amplitude and a one hundred and eighty degree phase shift from the interface 24 back to the piezoelectric crystal 10, as generally indicated by the lines 28. All portions of this half of the incident acoustical wave travel along paths of equal length in time and therefore arrive back at the piezoelectric crystal 10 at the same time.

Every notched end portion B includes a pair of adjoining notches 30. Each pair of adjoining notches 30 has a flat side 32 that makes an angle of ninety degrees with the reference plane 26 and has a pair of flat sides 34 of equal length that intersect one another at an angle of ninety degrees at the reference plane. One of these sides 34 makes an angle of forty-five degrees with the side 32, and the other makes an angle of forty-five degrees with one side of the termination 22 or with another flat side 32 that makes an angle of ninety degrees with the reference plane 26. The other half of the incident acoustic wave is therefore reflected twice with a minimum reduction of amplitude and a three hundred and sixty

degree phase shift from the interface 24 back to the piezoelectric crystal 10, as generally indicated by the lines 36. Every portion of this half of the acoustical wave travels along a path of the same length in time as that traveled by every portion of the other half of the acoustical wave. Thus, both halves of the incident acoustic wave arrive back at the piezoelectric crystal 10 at the same time. The effect upon the piezoelectric crystal 10 of one half of the incident acoustic wave is therefore cancelled by that of the other half since each half has substantially the same magnitude and is one hundred and eighty degrees out of phase with the other half. This prevents the piezoelectric crystal 10 from detecting the incident acoustic wave. Even if the effect upon the piezoelectric crystal 10 of the incident acoustic wave is not completely cancelled the detected incident acoustical wave is so reduced in magnitude as to be readily distinguishable from other detected acoustical waves.

In every case the dimensions of the flat and notched portions A and B of the termination 22 must be large enough to be good reflectors. Furthermore, the characteristic impedance Z_{01} of the termination 22 must always be greater than the characteristic impedance Z_{02} of the surrounding medium. When, as in the preferred embodiment described above, Z_{01} is very much greater than Z_{02} , there is approximately one hundred percent reflection from the interface 24. Substantially equal areas of the piezoelectric crystal 10 must then be positioned directly opposite the flat and notched end portions A and B of the termination 22. However, when Z_{01} is not very much larger than Z_{02} , there is less than one hundred percent reflection from the interface 24. In this case the areas of the piezoelectric crystal that are positioned directly opposite the flat and notched end portions A and B of the termination 22 must be adjusted in order to cancel, by phase interference, the portions of the incident acoustical wave that are reflected back to the piezoelectric crystal 10.

I claim:

1. An ultrasonic transducer comprising:
a transducer element;
a termination acoustically coupled to said transducer element, said termination having a characteristic impedance greater than the characteristic impedance of the adjacent medium, said termination having an end forming an interface with the adjacent medium, said end including indented regions arranged so that one portion of an acoustical wave generated by said transducer element is reflected from said interface one time more than the remaining portion and so that both portions are reflected back to the transducer element along paths of substantially equal length in time.
2. An ultrasonic transducer as in claim 1 wherein:
said transducer element has a pair of opposite and parallel faces;
said termination is acoustically coupled to one of the faces of said transducer element;
said end of the termination includes flat regions lying

40

45

50

55

in a reference plane parallel to the faces of said termination; and
each of said indented regions comprises a notched region.

3. An ultrasonic transducer as in claim 2 wherein each of said indented regions comprises a pair of adjoining notches, said pair of adjoining notches having a first flat side that makes an angle of ninety degrees with said reference plane and having second and third flat sides of substantially equal length that intersect one another at an angle of ninety degrees at said reference plane, said second side making an angle of forty-five degrees with said first side and said third side making an angle of forty-five degrees with a fourth side that is oriented at an angle of ninety degrees with respect to said reference plane.

4. An ultrasonic transducer as in claim 3 wherein said fourth side comprises one of a side of said termination and a side of said pair of adjoining notches.

5. An ultrasonic transducer as in claim 4 wherein:
said notched regions are collectively positioned directly opposite half of said transducer element; and
said flat regions are also collectively positioned directly opposite half of said transducer element.

6. An ultrasonic transducer as in claim 5 wherein:
said transducer element comprises a piezoelectric crystal having a first electrode bonded to one of said pair of opposite and parallel faces and having a second electrode bonded to the other of said pair of opposite and parallel faces; and
said termination is bonded to said second electrode.

7. An ultrasonic transducer as in claim 6 wherein said termination comprises an acoustically lossy material and has a characteristic impedance matched to that of said piezoelectric crystal.

8. An ultrasonic transducer as in claim 7 wherein said flat regions and said notched regions are alternately arranged across the end of said termination.
